UNITED STATES PATENT OFFICE.

FRANK HEDLEY EVANS, OF BEACONSFIELD, AND HAROLD AGUTTER EVANS, OF SOUTH HARROW, ENGLAND, ASSIGNEES TO GEORGE STANLEY WALPOLE, OF LONDON, ENGLAND.

EMBOSSING APPARATUS.

Application filed October 2, 1922. Serial No. 591,970.

To all whom it may concern:

Be it known that we, FRANK HEDLEY EVANS, a subject of the King of Great Britain and Ireland, and residing at Wilton 5 Cottage, Beaconsfield, in the county of Birmingham, England, and HAROLD AGUTTER EVANS, a subject of the King of Great Britain and Ireland, and residing at 26 10 Maybank Avenue, South Harrow, in the county of Middlesex, England, have made a certain new and useful Invention in Embossing Apparatus, of which the following is a specification.

This invention relates to embossing machines of the kind known as "cutter crush" machines such as are used for embossing letters, numerals or designs on cardboard or the like, and at the same time cutting out and punching colored paper or the like into recesses in the cards formed by the dies which latter are necessarily formed with cutting edges. In this way, by using cards of one color and pieces of paper or the like, or one or more card colors, together with suitable 20 dies, the machine can emboss words, letters, figures and designs in any desired color scheme on cards or the like, at one operation. These machines, while adapted for many different purposes, find particular application in the making of show cards, price 25 tickets and the like, for use in shops, places of business and exhibitions.

The object of the invention is to provide a cutter crush machine which is simple of 30 construction, efficient in operation and economical of manufacture.

A further object of the invention is to provide a machine of this character which affords many advantages over machines of other structure designed for the same or substantially the same purpose.

Further objects of the invention will appear more fully hereinafter.

The invention consists in the construction, combination, location and relative arrangement of parts, all as will be more fully hereinafter set forth, as shown in the accompanying drawing and finally pointed out in the appended claims.

Referring to the drawing:

Figure 1 is a longitudinal sectional elevation.

Fig. 2 is a transverse sectional elevation.

Fig. 3 is a plan view.

In order to give satisfactory results a machine to be used for the purpose of this invention must be simple in construction and operation, and which should require but one operator. It should be so constructed that the necessary pressure is in all cases applied with certainty and without undue effort. We have found that different shapes and sizes of dies are required to be impressed into the cards and that if the impression depth is insufficient the resulting effect is unsatisfactory, while too great a pressure will not only frequently spoil the effect but also cause the dies to wear out very rapidly. Finally, the machine must be so arranged that the pressure is evenly dissipated no matter what the position of the dies may be.

It is among the special purposes of our present invention to provide a machine which answers all of these requirements.

In accordance with our invention, we supply a machine consisting generally of a lower platen mounted on a table pivoted to the frame of a machine, an upper platen in fixed but adjustable relationship to the frame, and a cam shaft mounted in bearings in the frame and adapted to lift the table so that the work may be pressed between the two platens so adjusted that the maximum lift of the lower platen is parallel with the upper platen. We also provide means for adjusting the upper platen to any relationship relative to the frame to suit the thickness of the work or the desired depth of impression. Furthermore, we provide means whereby the dies may be readily changed and the parts requiring cleaning easily gotten to.

Referring to the drawings *b* designates the table which is pivoted to the bed plate *a*, as shown, a convenient distance remote from the center of the pressure application, as will be more fully hereinafter set forth. The lower platen *c* rests on the table and is movable backwards and forwards so as to facilitate the setting of the work. For this purpose a light metal frame *d* which can be easily handled, is fastened to the platen and extends therefrom along the direction of sliding relative to the table. Any suitable stop may be employed to determine the position of the platen for the application of pressure. Hardened steel pressure plates *e* are fastened beneath the table and nor-

mally rest on cams formed on the cam shaft *f* resting in bearings *h* on the bed plate. An operating crank *g* is geared or otherwise suitably connected to the crank shaft.

5 The bed plate carries four columns *i*, to the upper ends of which fasten a bridge piece *k* adapted to carry the upper platen *l*. In order to provide for the adjustment of the upper platen, we mount the same upon 10 the bridge piece by means of springs *m*, and interpose between the platen and the underside of the bridge plate, a wedge plate *n* which may be adjusted in position by a nut *o* on a stud *p* secured to the bridge piece, or 15 by other suitable means.

In operation, the lower platen is slid along the table until it is clear of the upper platen and the bridge piece, the cardboard with colored paper, is placed thereon, and the 20 punching and cutting types are placed in position on the cardboard, suitable stops, guides or the like, being provided on the platen if desired, for the purpose of positioning the work. The lower platen is then 25 slid along the table into its position for the application of the pressure.

The wedge plate *n* is adjusted so that when the table *b* has been lifted by the cams 4 into its highest position, the plane surfaces of the two platens *c* and *l* between which the work is pressed, are exactly parallel. In order to afford a wide range of 30 adjustment to suit different thicknesses of work, the distance of the bridge piece from the bed plate may be varied by means of 35 suitable nuts *s* secured on the columns *i*, as shown.

The upper platen having been adjusted to suit the thickness of the work, and the 40 lower platen with the work thereon having been slid into position, the operating lever *g* is turned until the cams have lifted the table into its highest position. The cams 4 shown on the drawing are such that the 45 operating lever would have to be moved at least 180 degrees. A suitable stop may be fixed to the frame to determine the position of the rest of the operating lever, if desired. The lever having applied the 50 pressure to the work, the table drops, the work is removed, and the shaft is then turned to its normal position without effort. Alternatively, instead of turning the crank 55 shaft towards and away from a stop, it may be made to make a complete revolution.

It will be apparent that it will be easy for a skilled operator to determine by one or two experimental operations what is the correct adjustment of the gap between the two 60 platens for the particular work and/or dies; the necessary adjustments being made to the wedge *n* by means of the screw *o*. When the machine has once been adjusted it 65 remains correctly set for repetitions of the same or similar work.

It should be noted that the pivot for the table *b* on the base *a* and the shaft *f* are so arranged relative to each other that at the point of maximum lift of the cam the table *b* is always parallel to the upper platen *l*. After the cam has passed its maximum lift 70 position the table drops which enables the work to be removed and the shaft to be returned to its inoperative position without effort.

When a large number of cards or the like of the same kind are to be produced, instead of placing the dies on the cardboard, as above described, they may be replaced by a die or dies fastened to the lower 80 surface of the upper platen. In this manner repetition work is more quickly performed.

It will be readily appreciated by those skilled in the art that the machine forming the substance of our invention, and to which the foregoing description has been directed, possesses many advantages over other previously known machines for the same purpose. By correctly adjusting the gap between the 85 platens the proper pressure is applied to the work provided the operating shaft is moved through its full distance as the cams must of necessity during this operation reach and pass the position of maximum lift. It is therefore not left to the operator to guess 90 when the correct pressure has been applied. The machine also answers the various requirements above referred to. The wearing parts are quickly accessible. On removing the lower platen and lifting the table by 100 hand towards the upper platen or bridge piece, the cam shaft can be instantly removed from the machine. The pressure plates can then be quickly removed and replaced when necessary.

Many other modifications and changes in details will readily occur to those skilled in the art without departing from the spirit and scope of our invention as defined in the claims, but having now set forth the objects 110 and nature of our invention, and having shown and described a structure embodying the principles thereof, what we claim as new and useful and desire to secure by Letters Patent is:

1. An embossing machine comprising a frame, a table hinged at one end to said frame, a lower platen normally carried by said table at an angle to the horizontal plane of said frame, a vertically adjustable upper platen, and means for raising said lower platen to a position of parallelism with respect to said upper platen.

2. An embossing machine comprising a frame, a table hinged at one end to said frame, a lower platen slidably mounted on said table and normally disposed at an angle to the horizontal plane of said frame, a vertically adjustable upper platen normally disposed parallel to the plane of said 120 125 130 135 140 145 150 155 160 165 170 175 180

frame, and means for raising said lower platen to a position of parallelism with respect to said upper platen.

3. An embossing machine comprising a frame, a table hinged at one end to said frame, a lower platen slidably mounted on said table and normally disposed at an angle to the horizontal plane of said frame, a bridge piece carried by said frame, an upper platen carried by said bridge piece normally in a plane parallel to the plane of said frame, means for vertically adjusting said upper platen with respect to said bridge piece without altering its parallel relations to the plane of said frame, and means for raising said lower platen to a position of parallelism to said upper platen.

4. An embossing machine comprising a frame, an upper platen supported thereby, a table hinged to said frame for movement with respect thereto, a lower platen carried by said table and disposed at an angle to said upper platen, and means for raising said table whereby said lower platen at the maximum upward movement thereof is parallel to said upper platen.

5. An embossing machine comprising a frame, an upper platen supported thereby, a table hinged to said frame for movement with respect thereto, a lower platen slidably carried by said table and disposed at an angle to said upper platen, and means for raising said table whereby said lower platen at the maximum upward movement thereof is parallel to said upper platen.

6. An embossing machine comprising a frame, an upper platen supported thereby and adjustable vertically with respect thereto, a table hinged to said frame for movement with respect thereto, a lower platen carried by said table and disposed at an angle to said upper platen, and means for raising said table whereby said lower platen at the maximum upward movement thereof is parallel to said upper platen.

7. An embossing machine comprising a frame, a table hinged at one end to said frame, a lower platen slidably mounted on said table and normally disposed at an angle to the horizontal plane of said frame, a bridge piece carried by said frame, an upper platen carried by said bridge piece normally in a plane parallel to the plane of

said frame, means including a laterally movable wedge for vertically adjusting said upper platen with respect to said bridge piece without altering its parallel relations to the plane of said frame, and means for raising said lower platen to a position of parallelism to said upper platen.

8. An embossing machine comprising a frame, an upper platen supported thereby, means including a laterally movable wedge for vertically adjusting said platen, a table hinged to said frame for movement with respect thereto, a lower platen carried by said table and disposed at an angle to said upper platen, and means for raising said table whereby said lower platen at the maximum upward movement thereof is parallel to said upper platen.

9. An embossing machine comprising a frame, a bridge piece adjustably supported by four columns mounted on said frame, an upper platen carried by said bridge piece, a wedge supported by said bridge piece and positioned between said platen and said bridge piece, means for moving said wedge laterally with respect to said bridge piece, a table hinged at one end to said frame, a lower platen carried by said table and disposed with the surface thereof at an angle to the surface of said upper platen, and means for moving said lower platen into parallelism with said upper platen.

10. An embossing machine comprising a frame, a bridge piece adjustably supported by four columns mounted on said frame, an upper platen carried by said bridge piece, a wedge supported by said bridge piece and positioned between said platen and said bridge piece, means for moving said wedge laterally with respect to said bridge piece, a table hinged at one end to said frame, a lower platen carried by said table and disposed with the surface thereof at an angle to the surface of said upper platen, and means carried by said frame for moving said lower platen into parallelism with said upper platen.

In testimony whereof we have signed our names to this specification.

FRANK HEDLEY EVANS.
HAROLD AGUTTER EVANS.
